Primary Examiner — Darlington Ly*Assistant Examiner* — Giang Hoang Tran(74) *Attorney, Agent, or Firm* — FINNEGAN, HENDERSON, FARABOW, GARRETT & DUNNER LLP(57) **CLAIM**

The ornamental design for a bicycle seating system, as shown and described.

DESCRIPTION

FIG. 1 is a front, right perspective view of a bicycle seating system, showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The broken lines of even length shown in the drawings illustrate portions of the bicycle seating system that form no part of the claimed design.
